UNITED STATES PATENT OFFICE.

GEORGE G. WEITZ, OF BOSTON, MASSACHUSETTS.

WATCHMAN'S ELECTRIC REGISTER.

SPECIFICATION forming part of Letters Patent No. 253,962, dated February 21, 1882.

Application filed August 24, 1881. (No model.)

To all whom it may concern:

Be it known that I, GEORGE G. WEITZ, a citizen of the United States, residing at Boston, in the county of Suffolk and State of Massachusetts, have invented certain new and useful Improvements in Watchmen's Electric Registers; and I do hereby declare that the same are fully described in the following specification and illustrated in the accompanying drawings.

This invention relates to improvements in watchmen's electric registers; and it consists, in such a register, of an electro-magnet and its movable armature and connecting mechanism to a spring-driver, by means of which the latter is wound up by the attractive power of the electro-magnet to move the stylus-bar across the face of the paper, as will be herein more fully shown and described.

Formerly the stylus-bar in watchmen's electric registers was actuated by a weight and separate clock mechanism to move it across the paper, which required the attention and manipulation of winding up, and if the said weight was not wound up at the proper time the stylus-bar would not travel across the paper, and would consequently not register until the weight was again wound up.

My invention is automatic in relation to actuating the stylus-bar, and in this invention the usual weight and superfluous clock-work are dispensed with for moving the stylus-bar, and the latter is actuated by a spring-driver automatically wound up by the initial blow of the armature-lever when the initial or first tooth of the contact-wheel in the box or transmitter strikes its contact-spring, as will hereinafter be more fully shown and described, reference being had to the accompanying drawings, in which—

Figure 1 represents a front elevation of the invention. Fig. 2 represents a side elevation. Fig. 3 represents a bottom view; and Fig. 4 represents a cross-section in the line A B, seen from α in Fig. 2.

Similar letters refer to similar parts wherever they occur on the different parts of the drawings.

a' represent the usual helices or coils of insulated wire, and a'' represents the conducting-wire from the battery b and box or transmitter C , as usual.

d are the soft-iron cores of the electro-mag-

net, and e is the movable armature secured to the hammer-lever f , the latter being hinged or loosely suspended in bearings at f' , as shown. 55

In the box or transmitter C , c is the contact-wheel, with its first or initial tooth, c' , and additional teeth $c'' c''$, according to the number of the box or transmitter, as usual.

c'' represents the usual contact-spring in the box or transmitter C .

e' represents the armature-lever, secured to the armature e in a suitable manner. e'' is the extreme projecting end of said armature-lever e' .

g is a ratchet-lever hung loosely at g' , and provided with pawls $g'' g'''$, which actuate the ratchet-wheel h when the armature-lever e' comes in contact with said ratchet-lever g during the initial blow of the armature e toward the electro-magnet. The ratchet-wheel h is attached to a pin or shaft, h' , that passes through the spring-case i , and within the latter is located the spring-driver k , one end of which is secured to the pin or shaft h' and the other end to the interior of the spring-case i , in the usual manner of connecting spring-drivers to their case and ratchet-wheel. 70

To the spring-case i is attached the escapement-wheel l , having teeth $l' l''$ engaging with the pallet m' on the upper end of the oscillating pendulum-bar m , having secured to it the adjustable pendulum m'' , as shown. 80

On the circumference of the spring-case i are located projections $i' i''$, which, in combination with the locking and releasing lever $n n'$, serve 85 to keep the spring-case i from turning after the spring therein is wound up until the projection e'' on the armature-lever e' comes in contact with the part n of said locking and releasing lever, when it is turned on its fulcrum n'' and its other part, n' , disengaged from one of the projections i' on the spring-case i . A light spring, n''' , serves to keep the lever end n' in contact with the circumference of the spring-case i when the end n is not acted on 90 by the projection e'' on the armature-lever e' . 95

On the circumference of the escapement-wheel l are located projections $l'' l''$, which serve two purposes--namely, first to act on the pin o' on the stylus-bar o , and thereby cause 100 the latter to move on its guide-bar p toward the right against the influence of the coiled spring q , during which motion of the stylus-bar o the impressions on the sheet of paper r

are produced, as usual, by the action of the hammer f'' on the stylus or marker o'' in the upper end of the stylus-bar o . When the stylus-bar o has been moved to its extreme right-hand position it is released by one of the projections l'' on the escapement-wheel l passing by the tooth or pin o' on the stylus-bar o , when the latter is automatically forced back toward the left to its original position by the influence of the spring q . The projections l'' also serve to act on the bent lever s , moving on the fulcrum s' and causing its upper end, s'' , to depress the wind-up lever g after the stylus-bar o is released, so as to be in position for the next initial blow of the armature-lever e' when the next box or transmitter is operated. $t t$ represent the feed-rolls for the paper, as usual.

The operation of the invention is as follows: In winding up a transmitter, C , its first or initial tooth, c' , in closing the current by contact with the spring c''' , causes an initial blow of the armature e onto the electro-magnet, and in so doing the armature-lever e' strikes the ratchet or wind-up lever g and winds the spring k sufficiently to carry the stylus-bar o across the paper r by the action of the escapement-wheel projection l'' acting on the stylus-bar projection o' , and when the armature-lever e' is near the end of its stroke its outer projection, e'' , comes in contact with the releasing-lever n , causing its end n' to be released from the projection i' on the spring-case i , by which the spring-case i and its escapement-wheel l are set in motion by the spring-driver k , and thereby causing the stylus-bar o to be carried against the influence of the spring q by the action of the projection l'' on the stylus-bar projection o' , during which time the armature-hammer f'' strikes the stylus or marker o'' and punctures the paper r as many times as there

are teeth on the transmitter contact-wheel c , excepting the first tooth, c' , which is the initial opening-tooth. During this operation the wind-up lever g is kept in a raised position by its pawls until the projection l'' on the escapement-wheel passes by the projection o' on the stylus-bar o , when the latter is actuated by the coiled spring q and carried back across the paper to its original position at the same time as one of said escapement-wheel teeth l'' comes in contact with the depressing-lever s'' , and actuates the latter to depress the wind-up or ratchet lever g to a position ready for the action of the armature-lever at its initial blow by winding any desired transmitter at any required station.

What I wish to secure by Letters Patent, and claim, is—

1. In a watchman's electric register, the electro-magnet $a a' d d'$ and movable armature e , and mechanism connecting it to the spring-driver k , by means of which the latter is wound up automatically by the attractive power of the electro-magnet, as described.

2. In a watchman's electric register, the combination of the movable armature e , armature-lever e' , winding-up lever g , ratchet-wheel h , pawls $g'' g'''$, spring-driver k , escapement $l l' l'' m m' m''$, locking and let-off lever $n n'$, projections $i' i''$ on spring-case i , projections $l'' l''$ on escapement-wheel l , the depressing-lever $s s''$, laterally-movable stylus-bar o , its tooth o' , and spring q , as and for the purpose set forth.

In testimony whereof I have affixed my signature in presence of two witnesses.

GEORGE G. WEITZ.
